CLAIM

The ornamental design for a handle for a power tool or similar article, as shown and described.

DESCRIPTION

FIG. 1 is a front elevational view of a handle for a power tool or similar article showing my new design, the rear elevational view being identical thereto;

FIG. 2 is a top plan view thereof;

FIG. 3 is a bottom plan view thereof; and

FIG. 4 is a right side elevational view, the left side elevational view being identical thereto.
